TELEGRAPH & TELEPHONE COMPANY LIMITED, OF LONDON, ENGLAND.

WIRELESS TRANSMISSION OF ELECTRIC ENERGY.

1,140,150.

Specification of Letters Patent.

Patented May 18, 1915.

Application filed February 18, 1913. Serial No. 749,150.

To all whom it may concern:

Be it known that I, ROBERTO CLEMENS GALLETTI, a subject of the King of Italy, and residing at 18 Cranley Place, London, S. W., England, have invented certain new and useful Improvements in and Relating to the Wireless Transmission of Electric Energy, of which the following is a specification.

10 This invention relates to a new method of transmitting electric energy at a distance without connecting wires and more particularly to a new system of transmitting and receiving wireless signals.

15 In ordinary wireless telegraphy and telephony use is made of high frequency oscillations flowing through an aerial at a transmitting station and producing electro-magnetic waves which are propagated through the space and act upon an aerial at a receiving station to produce therein high frequency oscillations which influence a detector arranged either in the aerial circuit or in another oscillating circuit suitably connected to the aerial, the detector acting upon a suitable indicating device such as a telephone or other instrument.

20 The main object of the present invention is to provide improved means for transmitting electric energy at a distance without connecting wires, and I have found that such means permit the reception of signals at a distant receiving station directly by an indicating device without the interposition of a detector or its equivalent.

25 The invention broadly consists in using at the transmitting station an aerial which is relatively slowly charged in one sense only and is impulsively discharged by means of a quenched spark also in one sense only, the object of such an arrangement being the production of rapid uni-directional discharges in the aerial circuit.

30 I wish it to be understood that the spark which I use to impulsively discharge the aerial is quenched to such an extent that no discharge takes place therein in the opposite sense, or if such discharge of opposite sense takes place the same is so small as compared with the main discharge that it has hardly any appreciable effect upon the electrical conditions of the aerial.

35 The invention also consists in a new system of wireless signaling in which the sig-

nals are transmitted by means of uni-directional impulses from an aerial as above referred to and such signals are received at a distant receiving station in the form of uni-directional currents in an aerial in which the formation of free oscillations is suppressed.

35 The invention further consists in the use of the particular arrangements hereinafter described for the purpose of carrying out the invention above referred to into effect.

40 Referring to the accompanying drawings, Figure 1 illustrates diagrammatically and by way of example a transmitting arrangement according to my invention. Fig. 2 is a diagrammatic detail, and Figs. 3 and 4 illustrate two receiving arrangements.

45 The arrangement illustrated in Fig. 1 is derived from the arrangement shown in Fig. 1 in the specification of my British Letters Patent No. 15497 of 1910, in which I have substituted the aerial for the regulating capacity C_0 and the form of multiple spark gaps forming the subject matter of my British Letters Patent No. 10639 of 1911, for the spark gaps shown in said figure. The positive or negative pole of a direct current dynamo D, preferably of high voltage, is connected through a conductor M and through the interposition of an inductive resistance R with the aerial a , and a plurality of multiple spark gaps $s_1 s_2 s_3 \dots s_n$ are interposed between the aerial and a plurality of condensers $c_1 c_2 c_3 \dots c_n$ having a common coating C which is connected to earth at b. The opposite pole (negative or positive) of the direct current dynamo is connected through a conductor N and through inductive resistance $r_1 r_2 r_3 \dots r_n$ with the ends of the spark gaps connected to the condensers $c_1 c_2 c_3 \dots c_n$ respectively.

50 The condenser coatings connected to the spark gaps are also connected to solenoids $d_1 d_2 d_3 \dots d_n$ arranged adjacently to the spark gaps, each of these solenoids being energized by the discharge of the spark gap circuit to which it is attached and starting a discharge in the spark gap in front of which it is arranged, whereby cyclical discharges are produced. These discharges take place at very small intervals of time, as described in the specification to my British Letters Patent No. 12633 of 1907, the capacity of the aerial forming in

series with each one of the condensers $c_1, c_2, c_3, \dots, c_n$ the capacity of each spark discharge, similar to the capacities $C_0, C_1, C_0, C_2, \dots, C_0, C_n$ in the specification to my British Letters Patent No. 15497 of 1910.

5 Let the discharge through the first multiple spark gap s_1 be started by any suitable means such as in the usual way by means of an induction coil; this discharge will cause 10 by propagation along the wire of the solenoid d_2 an electromagnetic field around the solenoid and this field will initiate a discharge across the second multiple spark gap s_2 ; the latter discharge will cause in its turn 15 an electromagnetic field around the solenoid d_3 and so on, the various discharges following one another in a cycle. When a discharge takes place at s_1 the potential of the aerial a is thereby reduced, such reduction in 20 potential being also effected at all the other spark gaps $s_2 \dots s_n$. The discharge through the latter spark gaps is prevented from taking place as long as there is a discharge through s_1 , but as soon as the latter disappears 25 the capacity of the aerial a is at once charged again by the current supplied from the dynamo D , whereby the tension in all the spark gaps is increased.

By the arrangement hereinbefore described 30 the aerial is continuously charged in one sense only and is discharged by means of rapid uni-directional impulses practically in a continuous manner, which rapid uni-directional impulses cause the transference 35 of electric energy through space at a considerable distance.

In applying the invention to telegraphic signaling I provide the following arrangement in order to have the cycles of discharges under the complete control of the transmitting Morse key or its equivalent.

Referring to Fig. 2, in front of one of the spark gaps $s_1, s_2, s_3, \dots, s_n$, shown in Fig. 1, say s_2 , I place a solenoid e which 45 is connected to and is excited by a separate spark circuit comprising two condensers f and f_1 , a small gap g and another gap h . This circuit is connected to the leads M, N from the direct current dynamo through the intermediary of inductive resistances R_1, R_2 , in such a way that the coating of the condenser f_1 which is connected to the solenoid e is charged at a potential which is of opposite sense to the potential of the coating 50 of the condenser to which the solenoid d_2 is attached. In the small gap g I place a Morse key i which is preferably connected to earth. As long as the gap g is open, the static influence of the direct charging current 55 from the dynamo has no influence upon the same, but the gap h is bridged by a uni-directional arc; as soon, however, as the gap g is closed by the key i the two condensers 60 form a capacity across the gap h , the arc across h is interrupted, and a spark dis-

charge takes place at regular intervals. At each discharge the solenoid e is energized and produces a field which causes a discharge through the gap s_2 thereby starting the cycle of discharges.

70 For telegraphic purposes it is desirable to have not only the starting of the cycle of discharges but also its interruption under the control of the transmitting key or the like, and this is preferably effected by bringing the ends e_x and d_x of the solenoids e and d_2 respectively, close to and at such a distance from each other that a spark discharge takes place between them when both coils are energized, thereby stopping the 75 cycle of discharges by the fields of the two coils neutralizing each other.

As it may be inconvenient (though not difficult) to arrange for the coincidence in 80 time of the fields of the solenoids d_2 and e , I prefer to provide the end of the solenoid e with a plurality of conductors leading 85 also to the proximity of the ends of the solenoids arranged along the other spark gaps of the discharge apparatus, the result 90 of this arrangement being that each time the field of the solenoid e is energized, cycles of discharges are alternately started from the spark gap s_2 , and stopped in the manner 95 above referred to by a spark discharge between the end e_x of the solenoid e and the end of that particular solenoid which is energized at the time the solenoid e is energized. The spark frequency of the spark 100 circuit $f f_1 h$ depends upon its capacity, the resistance of its supply leads and the discharge potential of the gap h , this frequency being chosen according to the speed 105 of the telegraphic apparatus controlling the key i , or adjusted to give the musical note required in the case of reception by sound.

At the receiving station the formation of free oscillations in the aerial is prevented 110 in order to permit the reception of uni-directional impulses, the simplest means for this purpose being the insertion therein of a sufficiently high ohmic resistance, such as that of a telephone or of a relay, as shown by the reference letters k and l in Figs. 3 and 4 respectively, by which arrangement signals 115 are received without the interposition of any kind of wave detector.

Having now described my invention, what I claim as new and desire to secure by Letters Patent is:-

120 1. A method of transmitting electric energy at a distance without connecting wires consisting in charging a transmitting aerial relatively slowly and in one sense only, and impulsively discharging it also in one sense only, as set forth.

125 2. A method of electric signaling without connecting wires, consisting in charging a transmitting aerial relatively slowly and in one sense only, and impulsively discharging 130

it also in one sense only, and in receiving the electric energy transmitted by the transmitting aerial in the form of uni-directional currents, as set forth.

5 3. A method of transmitting electric energy at a distance without connecting wires, consisting in charging a transmitting aerial relatively slowly and in one sense only, and automatically and partially discharging it

10 at very small intervals of time, also in one sense only, as and for the purpose set forth.

4. Apparatus for transmitting electric energy at a distance without connecting wires, comprising in combination a continuous current dynamo, an aerial connected with said

15 dynamo, a plurality of discharge circuits,

each of which comprises a quenched spark gap and a condenser having two armatures, one armature being connected with the ground and the other armature being connected with the dynamo, and a resistance between the latter armature and the dynamo, all the discharge circuits being connected in parallel with one another and in series with the aerial, as and for the purpose set forth. 20 25

In testimony whereof I have signed my name in the presence of two witnesses.

R. C. GALLETTI.
